UNITED STATES PATENT OFFICE.

GEORGE S. HERRICK, OF SYRACUSE, NEW YORK.

SHAKING-GRATE.

SPECIFICATION forming part of Letters Patent No. 689,645, dated December 24, 1901.

Application filed May 6, 1901. Serial No. 58,882. (No model.)

To all whom it may concern:

Be it known that I, GEORGE S. HERRICK, a citizen of the United States, and a resident of Syracuse, in the county of Onondaga, in the State of New York, have invented new and useful Improvements in Shaking-Grates, of which the following, taken in connection with the accompanying drawings, is a full, clear, and exact description.

This invention relates to the class of grates which are composed of a series of bars provided with pivotal bearings and with means for rocking said bars; and the invention consists in an improved construction of the grate-bars, which in their shaking or rocking motion effectually break the clinkers and thoroughly clean the bottom of the fire without incurring waste of fuel; and the invention also consists in the combination, with the pivoted grate-bars provided with depending crank-arms, of links coupling the successive crank-arms in pairs and allowing the grate-bars to be readily removed separately from each other when required for repairs or renewal of grate.

In the accompanying drawings, Figure 1 is a side view of a grate embodying my invention. Fig. 2 is a plan view of said grate. Fig. 3 is a plan view of the couplings which transmit motion to the grate-bars. Fig. 4 is a fragmentary side view of one of the end portions of the grate-bar. Fig. 5 is an end view of two adjacent grate-bars. Fig. 6 is a perspective view of a portion of one of the grate-bars, and Fig. 7 is a vertical transverse section on line X X in Fig. 1.

Similar letters of reference indicate corresponding parts.

A represents the frame, which supports the grate independently of the masonry surrounding the ash-pit. To adapt this frame for ash-pits of different depths, I form said frame with supporting-legs A', which are made adjustable in length, preferably by forming each of said legs of two end sections, one of which is provided with a vertical slot d and with sockets or mortises d' d' adjacent to the edges of said slot. The bolts e, which fasten said leg-sections together, pass with their screw-threaded ends through said slot and through holes in the companion leg-section and are provided with nuts n, by means of which the two leg-

sections are clamped together, while the heads n' of the bolts are seated in the mortises d' and prevent the upper leg-section from accidentally slipping down on the lower leg-section, as shown in Fig. 7 of the drawings. The top of said grate-supporting frame is provided with a series of recessed bearings a a for the trunnions t on the ends of the grate-bars c c. Each of these grate-bars is formed in one piece, with a series of vertical webs b b distributed over the length of the bar, with spaces c' c' between the webs. Each of these webs is formed with convex and concave top portions b' b' on opposite sides of the bar and with concaved edges b'' b'' under said top portions, as more clearly shown in Fig. 5 of the drawings. The successive webs of each bar are disposed in reversed positions 65 and with the intervening spaces c' c' in line with the spaces of the adjacent bars. The shaking of said grate-bars causes the convexed and concaved webs to thoroughly agitate the bottom of the fire and the clinkers 70 to drop onto the depressed concaved top portions b' of the webs, where said clinkers are broken by the concave bottom edges b'' of the webs of the adjacent bar descending while the concaved top portions b' are ascending. The 80 broken clinkers being thrown under the grate effectually cleans the bottom of the fire without danger of causing waste of fuel through the grate. Said grate-bars are provided at corresponding ends with fixed pendent crank-arms f, preferably formed integral with the bars and terminated with laterally-projecting trunnions f'. These trunnions couple successively in pairs by means of links l l, provided in their ends with eyes for receiving 90 through them the trunnions f'. One of the end links has connected to it a bar h, which extends through the front plate P and is connected to a lever L, fulcrumed on a stud i, projecting from said front plate. By operating 95 said lever reciprocating motion is imparted to the aforesaid links, which causes the crank-arms f to transmit rocking motion to the grate-bars.

The bearings a a are open at the top to allow the grate-bars to be readily lifted from the frame A when required for repairs or renewal, which is also facilitated by the use of the separable coupling-links l l.

What I claim as my invention is—

1. A grate composed of bars, each having projecting from it a series of vertical webs distributed over the length of the bar with 5 spaces between the webs, each of said webs formed with convex and concave top portions on opposite sides of the bar and the successive webs being disposed in reverse positions, and means for shaking said bars.
- 10 2. A grate composed of bars, each having projecting from it a series of vertical webs distributed over the length of the bar with spaces between the webs and disposed with said spaces in line with the spaces of the adjacent bars, each of said webs formed with convex and concave top portions on opposite sides of the bar and the successive webs being disposed in reverse positions, depending 15 crank-arms fixed to said bars, a coupling connecting the successive crank-arms, and means for imparting reciprocating motion to said coupling as set forth.
- 20 3. A grate composed of bars, each formed with vertical webs distributed over the length 25 of the bar with spaces between the webs, each of said webs formed with convex and concave top portions on opposite sides of the bar and the successive webs being disposed in reverse positions, depending crank-arms fixed to said bars and terminated with trunnions, links 30 coupling said trunnions in pairs, a rod connected to one of the end links, and a grate-
- shaking lever connected to said rod as set forth.
4. A grate composed of bars, each formed 35 with vertical webs distributed over the length of the bar with spaces between the webs, each of said webs formed with convex and concave top portions on opposite sides of the bar and the successive webs being disposed in reverse 40 positions and arranged to pass through the spaces of the adjacent bars, crank-arms fixed to said grate-bars, coupling-links connecting said crank-arms in pairs, and a lever connected to said links for imparting rocking 45 motion to the crank-arms as set forth.
5. The combination with the ash-pit and grate, of a frame provided with legs supporting the grate independently of the walls of the ash-pit, and each of said legs composed 50 of sections lapping endwise one upon the other, one of said sections provided with a vertical slot and with sockets in the side of the sections adjacent to the edges of the slot, and attaching-bolts passing through said slot 55 and through the other of said leg-sections and seated with their heads in the sockets and provided with nuts for clamping the leg-sections together substantially as set forth.
